ELECTRICAL CONTACT MEMBER FOR CONDUITS

Martin J. De Mask, Pittsfield, Mass.

Application October 2, 1934, Serial No. 746,548

10 Claims. (Cl. 247—3)

This invention relates to conduits for electrical conductors, and has particular reference to the provision of improved contact clips and means for securing them to bus bars within such conduits so that connection may be made to an outside line by a plug or switch. One object of the present invention is to provide improved clip structures which will be engaged by the plug or switch blades and which will avoid direct contact 10 between the bus bars and the switch or plug blades, so that the arcing which occurs when the blades are withdrawn with the current on will not damage the bus bars. Another object is to provide an improved contact clip 15 which can be adjusted along the length of the bus bar. Another object is to improve upon the structure of the clips so that the contact will be improved. Additional objects will appear from the following description and claims.

20 This application is a continuation in part of my prior applications Serial Numbers 466,803, 610,298, and 620,707 and which have become Patents Numbered 1,992,816, 2,054,193, and 1,982,152 respectively.

25 Referring to the drawing.

Fig. 1 is a side elevation, partly in section, showing the clip of Fig. 3 in place on a conduit;

Fig. 2 is a transverse section through the conduit shown in Fig. 1;

30 Fig. 3 is a perspective detail of one form of clip;

Fig. 4 is a view similar to Fig. 1, but showing a modified form of clip;

Fig. 5 is a transverse section, on an enlarged 35 scale, of the clip shown in Fig. 4;

Fig. 6 is a perspective detail of the clip shown in Fig. 4; and

Fig. 7 is a perspective detail of a modified form of clip.

40 In the form shown in Figs. 1 and 2, the conduit is indicated as an entirely by the numeral 20, and comprises a metallic casing or shell which is furnished in sections adapted to be aligned and secured to the wall of a room or other 45 fixed support, the sections being provided in such lengths as may be conveniently handled. Each shell is preferably provided with a lining of insulation, as shown at 21, and within the shell are mounted longitudinal bus bars 22 for conducting current through the conduit. At intervals in the lengths of the bus bars, contact clips are secured thereto with which contact may be made by the blade 23 of a suitable switch mechanism or other contact device here shown as contained in an external casing 24. The switch

blade 23 is here shown as of an oscillating type, and the contact clip, one form of which is shown in Fig. 3, is therefore designed to receive the switch blade as the latter moves in a direction generally longitudinal of the bar.

5 The clip comprises a strip 25 held to the bus bar as by screws 26, and is bent reversely upon itself at 27 to form a resilient clip portion 28. This is provided with an outwardly flaring end 29 facilitating the entrance of the switch blade, 10 and has preferably an outwardly bent lip 30 at the bottom so as to adapt the clip for the reception of the blade of a switch or plug moving up from below in a vertical direction. The edge of the strip 25 may be beveled as at 33, 34, in order 15 to facilitate the entrance of the blade 23. The strip 25 may also be shortened, if desired, so that the bevel 33 will be positioned opposite the outwardly flared end 29. As an alternative, the clip shown in Fig. 3, may be modified as in 20 Fig. 7, where the body 25 is offset at 41 to form a beveled portion directing the contact blade into position between the clip jaws. This forms a somewhat more resilient clip than the clip shown in Fig. 3. In some instances the reversely bent 25 portion 28 shown in Figs. 3 and 7 may be omitted.

A somewhat similar form of clip is shown in Figs. 4, 5, and 6, having, however, distinct features and advantages of its own. The conduit 45 and the cooperating switch blade 46 are shown in 30 Fig. 4 as of the type described in my prior application Ser. No. 620,707. Bus bars 47 are carried within the conduit by suitably insulated hangers 48, and the clips, shown best in Figs. 5 and 6, are designed to be carried by a portion of the bus bar. 35 This location has definite advantages since there is less danger of injury to the conduit and less liability of short circuiting if arcing occurs when the blade 46 is withdrawn from the clip.

The clip itself has a U-shaped body portion 50 40 adapted to embrace the bus bar 47, one leg of the U being reversely bent upon itself at 51 so as to grip the blade 46. The end of this reversely bent portion is turned outwardly at 52, and the adjacent end of the U-shaped member is beveled off at 53 45 to facilitate the blade's entrance. The clip is held in place by screws 54 threaded through bosses 55 on the rear leg of the U, and bearing against the bus bar to give anchorage to the clip and at the same time to insure a good electrical contact with 50 the bus bar. This manner of securing the clip requires no threaded holes in the bus bar, and lends itself particularly to cases where the clips are to be put in place after the bus bars have been assembled in the conduits. A permanent 55

anchorage can easily be given if desired by notching the bus bar at 541 to receive the cross member of the U-shaped clip body. It will be readily understood that while the contact elements of the present disclosure are described as being enclosed within conduits, they might also be used outside of conduits, and unenclosed.

I claim:

1. In a system for distributing power, a conduit, a bus bar disposed therein, means for supporting said bar within said conduit, a contact clip having opposed walls spring pressed toward each other and means for holding said clip within said conduit and electrically connected to said bar, 10 said clip being positioned to receive a contact making blade, the spring pressed walls of said clip being arranged to embrace a blade with one wall of the clip interposed between the embraced blade and the adjacent bar whereby contact is maintained between said blade and said clip and contact between said blade and said bar is avoided.
2. In a system for distributing power, a bus bar, means for supporting and insulating said bus bar, a contact clip having jaws adapted to frictionally 25 engage an inserted terminal, said clip having an extension hooked over the adjacent bus bar, and means securing said extension to said bus bar.
3. In a system for distributing power, a bus bar, a contact clip formed with a side wall secured 30 to the bus bar, said wall being bent reversely upon itself to provide a resilient portion located alongside the first named wall, the adjacent surfaces of the resilient portion and the first named wall forming opposed contact areas for engagement by a contact element.
4. In a system for distributing power, a bus bar, a contact clip formed with one wall secured to the bus bar and extending longitudinally along the same, said clip being bent outwardly away 40 from the bus bar and then extending longitudinally along the bus bar to form an offset portion spaced from the bus bar, said offset portion being bent reversely upon itself to provide a resilient portion located alongside the offset portion, the resilient portion having an outturned lip located substantially adjacent said outwardly bent portion to facilitate the entrance of a contact prong between it and the first named wall.
5. In a device for distributing electrical power, 50 an extended bus bar, a contact clip comprising a portion extending longitudinally along one side of the bar and forming a contact area for frictional engagement by a contact blade, and an

extension from the said portion hooked over the bar and lying along the opposite side of the bar from the said portion, and means for securing the said extension to the bar.

6. In a device for distributing electrical power, 5 an extended bus bar, a contact element secured to the bar, the said element consisting of a strip extending longitudinally along one side of the bar and forming a contact area for frictional engagement by a contact blade, the said strip being interposed between the blade and the bar so that contact between the blade and the contact area is maintained and contact between the blade and the bar is avoided.

7. In a device for distributing electrical power, 15 an extended bus bar, a contact clip formed with a side wall secured to the bar and extending longitudinally along the bar, said wall being bent outwardly away from the bar and then longitudinally of the bar to form a portion spaced from the bar, 20 said spaced portion forming a contact area for frictional engagement by a contact blade.

8. In a device for distributing electrical power, 25 an extended bus bar, a contact clip formed with a side wall secured to the bar and extending longitudinally along the bar, said wall being bent outwardly away from the bar and then longitudinally of the bar to form a portion spaced from the bar, 30 said spaced portion being bent reversely upon itself to provide a resilient portion located alongside the said spaced portion, the adjacent surfaces of the spaced portion and the resilient portion forming opposed contact areas for frictional engagement by a contact blade.

9. In a device for electrical distribution, an 35 extended bus bar, a contact clip having a side wall secured to the bar and extending longitudinally along the bar, said wall being bent reversely upon itself to provide a resilient portion located 40 alongside the first named wall, the adjacent surfaces of the first named wall and the resilient portion forming opposed contact means for contact by a contact element, the said first named wall extending along the bar beyond the said resilient portion.

10. In a device for electrical distribution, an extended bus bar having a notch in a side, a contact clip positioned on said bar, said clip having a portion hooked around the bar and in engagement with said notch whereby movement of the 50 clip lengthwise of the bar is prevented.

MARTIN J. DE MASK.
